UNITED STATES PATENT OFFICE.

LOUIS A. STRAUBEL, OF GREEN BAY, WISCONSIN.

PAPER-CUTTING MACHINE.

Application filed February 27, 1923. Serial No. 621,561.

To all whom it may concern:

Be it known that I, LOUIS A. STRAUBEL, a citizen of the United States, and resident of Green Bay, in the county of Brown and State of Wisconsin, have invented certain new and useful Improvements in Paper-Cutting Machines; and I do hereby declare that the following is a full, clear, and exact description thereof.

10 This invention relates to paper cutting machines and is particularly directed to a machine for cutting bundles of interfolded sheets into lengths suitable for commercial packages.

15 In general, this invention is an improvement over that disclosed in Patent No. 1,452,227 issued to me April 17, 1923, for paper cutting machine, and has the same general objects as those disclosed in such 20 application.

At the present time, it is common practice to put up in packages, interfolded sheets of toilet paper, paper toweling, and the like, in which the ends of each sheet are interfolded with the ends of the adjacent sheets. This interfolding operation is performed on exceedingly wide sheets, resulting in a long bundle which has to be cut into proper commercial length or packages. This particular interfolding arrangement of the sheets of paper results in a bundle having lesser density at the folded edges than in the center, due to the fact that the end of the paper disposed between the adjacent 25 fold does not reach to the crease of the fold, leaving only two thicknesses of paper on the folded edge, with three thicknesses in the center.

40 In using the ordinary paper cutter it is necessary to press the sheets solidly together to obtain a clean cut, and this being impossible with the interfolded arrangement above described, the edges are left rough and uneven.

45 A further difficulty encountered in cutting elongated interfolded paper stock in the shorter lengths is due to the fact that it is impossible for the knives to cut a kerf in the paper, as no portion of the paper is cut away in the form of shavings or dust.

50 In cutting paper the portions of the paper are merely severed without removing any portion thereof, and it is therefore apparent that considerable pressure must be 55 exerted upon the rotary cutters to force

them between adjacent portions of the stock while they are making their cutting stroke. Obviously, a rotary cutter is of relatively large diameter, and in order to provide the requisite stiffness would necessarily have to be fairly thick. This thick cutter would tear the paper as it was forced through and leave a rough, frayed edge. On the other hand, a relatively thin cutter will spring and move from side to side, thereby making an irregular and unsatisfactory cut, if not, in fact, wrecking the cutter.

This invention is designed to overcome the above noted defects, and objects of this invention are, therefore, to provide a machine for cutting elongated interfolded paper stock into shorter lengths in which a smooth, even cut is obtained; in which relatively thin cutters may be employed; in which guiding means for the cutters are provided, whereby they may be forced between adjacent portions of the stock without danger of buckling or swaying of the cutters, and without producing any frayed or irregular edge in the severed paper.

Further objects are to provide a machine which will make a clean cut through the paper, irrespective of variations in the extent of compression of the different portions of the folded paper stock, and to provide a machine in which the folded paper stock may be readily handled in an effective and rapid manner.

An embodiment of the invention is shown in the accompanying drawings, in which—

Figure 1 is an elevation of the machine.

Figure 2 is a sectional view on the line 2—2 of Figure 1.

Figure 3 is a somewhat diagrammatic view corresponding to Figure 2 and showing a slight change in the machine, adapting it for cutting a slightly different form of interfolded paper stock.

Referring more particularly to the drawings, it will be seen that the machine comprises a pair of side standards 1 and 2, between which the carrier for the paper stock and the rotary cutters are mounted. The carrier comprises end spider members 3, which are rigidly secured to a shaft 4 journaled in the side standards and are provided with a plurality of regularly spaced outwardly projecting rectangular portions 5.

Channel irons 6 fit over and are secured to these rectangular projecting portions 5.

as may be seen from Figure 2, and extend from one spider to the other, thereby forming a real light structure. A plurality of aligned stock receiving pockets are secured to each of the channel members 6, and such pockets each comprise an inner and an outer jaw, indicated at 7 and 8, respectively, which are reinforced by suitable flanges 9. These inner pockets are rigidly secured to the channel members 6 and may be conveniently provided with a forward inwardly directed lip 10, which overhangs the forward edge or leading edge of the channel member 6 to thereby aid in positioning and maintaining the position of the pockets with reference to the channel members 6.

These pockets are ranged in rows, as may be seen in Figure 1, one row being carried by each of the channel members 6. They are so positioned that the adjacent edges 11 and 12 of their jaws are parallel and are closely spaced, permitting the rotary cutters 13 to slide therebetween and to be guided thereby, while such cutters are in active cutting operation.

It is to be noted particularly from reference to Figure 2, that the cutters 13 are guided both above and below the interfolded paper stock 14, and are therefore prevented from swaying or buckling. The cutters, therefore, may be made as thin as desired without danger of effecting an irregular or ragged cut through the paper stock. If desired, the adjacent edges 11 and 12 of successive pockets may be hardened in any suitable manner.

The cutters 13, as stated, are relatively thin, circular discs, and are regularly mounted upon a driving shaft 15 in spaced relation, corresponding to the spacing between the successive stock-carrying pockets. The shaft 15 is journaled in the upper portion of the side brackets 1 and 2 and is positively connected with the shaft 4 through suitable gearing indicated generally at 16.

Any suitable means may be provided for driving the machines,—for instance, a belt receiving pulley 17 may be connected with the shaft 15 by suitable gearing indicated generally at 18.

In the form shown in Figure 2, the cutters 13 travel in a clockwise direction, while the carrier travels in a counterclockwise direction. This insures a sheer cut edgewise of the stock, and it will be observed that due to the direction of rotation of the knife or cutter and the carrier, the tendency is to compress the interfolded sheets of paper into the pockets.

The sheets of paper constituting the paper stock indicated in Figure 2 have a single fold, while the paper stock indicated at 19 in Figure 3 have a double fold. This form of interfolded stock may be positioned within the pockets, as indicated in Figure

3, and the direction of rotation of the knives or cutters 13 is counter-clockwise, in this case, so as to insure a clear, even cut edgewise of the paper—such reverse direction of rotation of the cutter being secured by slightly altering the gearing, indicated generally at 16 in Figure 1, in a well-known manner.

It will be seen, therefore, that a paper cutting machine has been provided in which extremely thin rotary cutters may be employed; in which an even, smooth cut is secured; and in which the cutters are guided by the stock carrying pockets.

It will further be seen that a very simple construction has been attained in which it is not necessary to employ strippers for the cutters or additional guides for such cutters, but in which the essential guiding action is secured by means of the cooperation of the pockets themselves with the thin rotary cutters.

It is further to be noted that in the usual paper cutting machine where interfolded, elongated paper stock is employed, that the wrapper, or label, which surrounds the interfolded paper, becomes slack on the sides, or bulges out on such sides. Obviously, this condition aggravates the tendency to tear the paper and in the usual type of machines, the wrapper is very readily torn and frayed. However, in practicing this invention the wrapper, although it may have become slack, is cut with a clean, straight edge, without any fraying and, therefore, presents a slightly and attractive appearance.

I claim:

1. A paper cutting machine comprising a movable carrier for the paper, and a plurality of circular knives, said carrier having a plurality of slots through which said knives pass and the portions of the carrier adjacent said slots forming guides for said knives.

2. A paper cutting machine comprising a rotary carrier having a plurality of pockets having radially spaced inner and outer portions adapted to receive the paper, said portions having closely spaced juxtaposed portions, and a plurality of thin rotary knives positioned between said juxtaposed faces and contacting therewith, whereby said knives are guided by said carrier.

3. A machine for cutting elongated folded paper stock comprising a rotary carrier having a plurality of aligning pockets for said stock, said pockets being closely spaced and portions thereof adjacent the spaces forming guiding surfaces, and rotary cutters adapted to enter said spaces and guided by said surfaces.

4. A machine for cutting elongated folded paper stock into shorter lengths comprising a rotary carrier having a plurality of rows of aligned pockets, each row adapted to re-

ceive a length of stock and to support it substantially through its entire length, the successive pockets of each row having closely spaced parallel edges, a plurality of thin rotary cutters adapted to enter the spaces between the pockets and to be guided by the said parallel edges, and means for rotating said knives and carrier.

5. A machine for cutting elongated folded paper stock into shorter lengths, comprising a carrier having a plurality of aligned pockets adapted to receive said elongated stock, successive pockets being closely spaced and having parallel hardened faces, a plurality of thin revolvably mounted cutters adapted to enter the space between successive pockets, and means for rotating said carrier and cutters.

6. A machine for cutting elongated folded paper stock into shorter lengths, comprising a carrier having plurality of rows of aligning pockets adapted to support said elongated stock throughout substantially its entire extent, successive pockets having closely spaced parallel edges, means for advancing said carrier, and a plurality of relatively thin rotary cutter knives adapted to enter

the space between successive pockets and to be guided by said parallel edges.

7. A paper cutting machine comprising a carrier having a plurality of aligning pockets adapted to receive elongated stock and to support such stock throughout substantially its entire length, said pockets having inner and outer surfaces adapted to receive the stock between them, the surfaces of each successive pocket being in close proximity to the next adjacent pocket, and a plurality of thin rotary cutters adapted to pass between successive pockets and to contact with the adjacent surfaces of adjacent pockets to be guided by the outer and inner portions of said pockets, whereby said cutters are supported against lateral deflection above and below the paper stock during the cutting operation, and whereby cutters which are inherently too fragile to operate independently of the pockets may be employed.

In testimony that I claim the foregoing I have hereunto set my hand at Green Bay, in the county of Brown and State of Wisconsin.

LOUIS A. STRAUBEL.
